Primary Examiner — Susan Bennett Hattan*Assistant Examiner* — Brett Miller(74) Attorney, Agent, or Firm — Stetina Brunda Garred & Bucker(57) CLAIM

The ornamental design for a water bottle, as shown and described.

DESCRIPTION

FIG. 1 is a perspective view of a water bottle showing my new design;

FIG. 2 is a front, rear, left side and right side views of the water bottle shown in FIG. 1, each view identical;

FIG. 3 is a top view of the water bottle shown in FIG. 1; and, FIG. 4 is a bottom view of the water bottle shown in FIG. 1. The broken lines depict portions of the water bottle that form no part of the claim.
